(57) **CLAIM**

The ornamental design for a plasma connector liner, as shown and described.

DESCRIPTION

FIG. 1 is an isometric top view of a plasma connector liner showing my new design, the isometric bottom view being identical;

FIG. 2 is a side elevational view thereof, the opposite side elevational views being identical;

FIG. 3 is a top view thereof, the bottom view being identical; and,

FIG. 4 is a cross sectional view taken along lines 4-4 in FIG. 2.

The surface shading in FIGS. 1-4 and the cross hatching in FIG. 4 indicate a refractory material.
